(57) CLAIM

The ornamental design for a brush, as shown and described.

DESCRIPTION

FIG. 1 is a perspective view of a brush showing my invention;

FIG. 2 is a front side view thereof, with the bristles removed for clarity;

FIG. 3 is a back side view thereof, with the bristles removed for clarity;

FIG. 4 is a left side view thereof, the right side being a mirror image thereof;

FIG. 5 is a top side view thereof; and,

FIG. 6 is a bottom side view thereof, with the bristles removed for clarity.

The broken lines of the hole and the bristles are for illustrative purposes only and form no part of the claimed design. The bottom face of the brush head section, as indicated by broken lines in FIGS. 2 and 6, is also for illustrative purposes only and form no part of the claimed design.
